(57) CLAIM

The ornamental design for a cord clip, as shown and described.

DESCRIPTION

FIG. 1 is a front, top, and left side perspective view of a cord clip showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof; and,

FIG. 8 is a front, top, and left side perspective view thereof showing an attachment to a cord and to a horizontal pole. The broken lines showing a cord and pole in FIG. 8 illustrate environmental subject matter and form no part of the claimed design.

The broken lines showing a horizontal pole in FIG. 8 are for illustration purposes and form no part of the claimed design.

1 Claim, 4 Drawing Sheets
